ATTORNEY

UNITED STATES PATENT OFFICE.

FRANK J. FULLER, OF SAN FRANCISCO, CALIFORNIA.

TEST-TANK.

1,371,751.

Specification of Letters Patent. Patented Mar. 15, 1921.

Application filed December 24, 1919. Serial No. 347,154.

To all whom it may concern:

Be it known that I, FRANK J. FULLER, a citizen of the United States, residing at San Francisco, in the county of San Francisco and State of California, have invented new and useful Improvements in Test-Tanks, of which the following is a specification.

This invention relates to test tanks, or more particularly to containers of a water proof character for holding water or other fluid and adapted for testing or locating small punctures or ruptures in the inner tube of a pneumatic tire.

An object of the invention is to provide a collapsible tank adapted to be folded compactly in order that it may be placed beneath the seat or in the tool box of an ordinary automobile.

It is also an object of the invention to provide a tank as above described which will have supporting means or legs and said means being adapted to be also used as a bail or handle for lifting or carrying the same.

It is a general object of the invention to provide a device as above characterized which is rigid in construction when in its unfolded position, durable, and inexpensive to manufacture.

With the above, and other objects, the invention consists in the novel features of construction, combination and arrangement of parts to be hereinafter more fully described, claimed and illustrated in the accompanying drawings, in which:—

Figure 1 is a perspective.

Fig. 2 is an end elevation.

Figs. 3 and 4 are enlarged detail views showing the detachable and locking joint 40 in the link members between the legs or supports of the tank.

Figs. 5 and 6 are enlarged detail views showing the connecting and locking means between the two members of the main frame.

Referring to the drawings in detail, 10 indicates a bag or container which is preferably made of canvas treated with some water proof compound. A frame rectangular in shape and constituting the two U-shaped members 11 and 12 is provided, the U-shaped members being pivotally connected at their free ends by the rivets or bolts indicated at 13. The upper marginal edge of the canvas bag 10 is lapped over and sewed 55 so that it is securely connected to the two frame members 11 and 12, a part of the

marginal edge of the canvas bag being cut away as indicated at 14 to permit the two members 11 and 12 to be folded one upon the other as will later appear. In further 60 describing the manner in which the U-shaped frame members 11 and 12 are connected, it is to be observed that the respective free ends thereof overlap one another, and near one end of each U-shaped member 65 I provide a bolt or pin indicated at 15, and in alignment therewith in the opposing end of the U-shaped members, I provide an opening indicated at 16, Fig. 6. The pin or bolt 15 is firmly secured within the member in 70 which it is first inserted. When it is desired to fold the one U-shaped member upon the other, it is only necessary to spring outwardly the side of the U-shaped member within which the pin 15 extends and simultaneously doing the same with the opposite side. Thus, as will be obvious, the members 75 will be free to swing upon the pivots 13.

As shown by the drawings, the end walls of the tank 10 are sloped inwardly and thus 80 providing a longer tank at the top in order to permit the inner tube when folded to be easily inserted therein, and also to use a minimum of water to accomplish the purpose desired. In order to hold the tank or 85 its walls in their stretched or expanded position, I provide the U-shaped members 17 which are pivotally connected at their free ends to the inner sides of the U-shaped members 11 and 12 by rivets or otherwise, as indicated at 18. As is obvious, when these 90 members are swung downwardly and at right angles to the frame members 11 and 12, the walls of the bag 10 are extended and the container as a whole held in its normal 95 shape or form.

In order to provide supports or legs for the container, I provide the two U-shaped members 19 which are pivoted to the outer sides of the main frame members 11 and 12 by the same rivets or bolts by which the members 17 are pivoted. These supporting members or legs can be dropped down at right angles to the main frame and thereby support the same. In order to hold the supporting members in spaced relation with one another, I provide the two link members 20 and 21 which are detachably connected and adapted to be locked against longitudinal movement with respect to each other when 105 connected. One end of each of these members 20 and 21 is pivotally connected to the 110

respective cross portions of the legs or supporting members 19, and preferably so pivoted near the one side thereof as I have illustrated in Fig. 1. When the two link members 20 and 21 are detached, they are free to swing in alinement with the transverse portions of the supporting members 19 and adapted to lie within the sides thereof. For detachably connecting the free ends of members 20 and 21, I provide in one of the members a key hole slot indicated at 22, Fig. 4, and near the end of the other link I provide a rivet or bolt indicated at 23, Fig. 3. One head of the rivet 23 extends above the link 20 in which it is secured. On the link 21, I provide a flat resilient member 24 having its one end turned upwardly as indicated at 25 and its other end riveted to the link member 21. The narrow portion of the key hole slot 22 is adapted to receive the longitudinal portion of the rivet 23 extending above the link member 20, and when the rivet is slipped into said slot, its upper head engages the upturned portion 25 of the resilient member 24 and thereby holds the same against further longitudinal movement. In this manner, the legs or supporting members 19 are held in spaced relation with one another, and when it is desired to detach the link members 20 and 21, it is only necessary to press the leg members 19 toward each other and in this manner to bring the head of the rivet 23 into the larger opening of the key hole slot 22, said opening being adapted to permit the head to slide therethrough. In respect to the operation of my invention above described, assuming that the same is in its unfolded position as indicated in Fig. 1, and it is desired to fold the same, preparatory for placing beneath an automobile seat or other receptacle in the automobile, the first step would be to disconnect the link members 20 and 21 from one another and then draw them into alinement with the transverse portions of the supporting members 19. After this the supporting members 17 may be brought into alinement with their respective main frame members 11 and 12. Now the frame members may be folded one upon the other, and in this manner a compact formation of the device may be had. It is also to be noted that the supporting members 19, after being detachably connected by the link members 20 and 21 may be swung above the frame members 11 and 12 to a position where they may be used as a bail or for lifting the tank or transporting the same. While I have herein described my invention as a test tank for testing inner tubes of pneumatic tires, yet it is to be understood that my invention is applicable to other uses without any great modifications. One particular use which may be here noted is that

my invention may be used for carrying water to fill the radiator of an automobile engine when at some isolated spot. The invention is particularly adapted for this in its construction in that by tipping the tank in such a manner that the water will flow out of one corner, the stream can be thus made to such a thickness that the water can be easily poured into the radiator.

Having thus described my invention, what I claim and desire to secure by Letters Patent is:—

1. A collapsible container of the class described, a main frame to which the marginal edge of said container is secured, U-shaped supporting members pivotally connected at their free ends to the sides of said main frame, said U-shaped members being adapted to be swung into alinement with said main frame, detachable means between said U-shaped supporting members to hold said members in spaced relation when in their supporting position, said means comprising two link members one end of which is pivotally connected to the respective U-shaped supports, and means for detachably coupling their free ends when in extended position.

2. A collapsible container of the class described, a main frame to which the marginal edge of said container is secured, U-shaped supporting members pivotally connected at their free ends to the sides of said main frame, said U-shaped members being adapted to be swung into alinement with said main frame, detachable means between said U-shaped supporting members to hold said members in spaced relation when in their supporting position, said means comprising two link members one end of which is pivotally connected to the respective U-shaped supports, means for detachably coupling their free ends when in extended position, and means for locking said link members against longitudinal movement.

3. A collapsible container, comprising a pair of main frame U-shaped members pivotally connected at their free ends and carrying means for locking said main frame members when extended in opposite directions, a flexible container with its marginal edge secured to said main frame members, a pair of U-shaped members pivotally connected to the sides of each main frame member by the same pivoting means, one member of each pair being adapted to swing within the main frame members and the walls of the container and the other member of each pair being adapted to swing about the end portions of the main frame members.

4. A collapsible container, comprising a pair of main frame U-shaped members pivotally connected at their free ends, a flexible container with its marginal edge secured thereto, a pair of U-shaped members one of which is pivotally connected at its free ends

to the sides of the main frame members and adapted to swing about said main frame members and act as a support or bail for said container, means for holding said last 5 mentioned U-shaped members in spaced relation when serving as supports, said means comprising two link members each pivotally connected at its one end to the U-shaped supports and adapted to swing within said 10 supports and connecting means on the free ends of said links.

5. A collapsible container, comprising a pair of main frame U-shaped members pivotally connected at their free ends, a flexible 15 container with its marginal edge secured thereto, a pair of U-shaped members one of which is pivotally connected at its free ends to the sides of the main frame members and adapted to swing about said main frame

members and act as a support or bail for said 20 container, means for holding said last mentioned U-shaped members in spaced relation when serving as supports, said means comprising two link members each pivotally connected at its one end to the U-shaped supports, and connecting means on the free ends of said links comprising a resilient tongue member secured to one of the links and extending over a key hole slot provided in the link, and a projecting bolt head carried by 25 30 the other link member.

In testimony whereof I have hereunto set my hand in the presence of two subscribing witnesses.

FRANK J. FULLER.
